DESIGN FOR A SHOE

Hans H. C. Odencrants, St. Louis, Mo., assignor to Valley Shoe Corporation, St. Louis, Mo., a corporation of Missouri

Application June 10, 1936, Serial No. 63,193

Term of patent 3½ years

To all whom it may concern:

Be it known that I, Hans H. C. Odencrants, a subject of the King of Sweden, residing at the city of St. Louis, State of Missouri, have invented a new, original, and ornamental Design for a Shoe, of which the following is a specification, reference being made to the accompanying drawing, forming a part thereof, in which Figure 1 is a plan view and Figure 2 is a perspective view of a shoe embodying my design.

I claim:

The ornamental design for a shoe, substantially as shown.

HANS H. C. ODENCRAANTS.
